COVER FOR LIQUID ANIMAL FEEDER

Leighton G. Dotson, 9443 Sherwood Glen,
Dallas, Tex. 75228

Filed Nov. 17, 1969, Ser. No. 20,144

Term of patent 14 years

Int. Cl. D30—02

U.S. Cl. D30—13

FIG. 1

FIG. 5

FIG. 2

FIG. 3

FIG. 4

FIG. 1 is a perspective view of a cover for liquid animal feeder showing my new design;

FIG. 2 is a top view thereof;

FIG. 3 is a front view thereof;

FIG. 4 is a rear view thereof; and

FIG. 5 is an end view thereof.

The side not shown is the same as the side illustrated. The bottom is the inverse molded pattern of the top view.

I claim:

The ornamental design for a cover for liquid animal feeder, as shown and described.
